Patented Aug. 30, 1955

175,465

COMBINED DIAL AND HANDS FOR A CLOCK OR SIMILAR ARTICLE

Franklin Eugene Gilson, Upland, Calif.

Application March 17, 1954, Serial No. 29,584

Term of patent 3½ years

(Cl. D42—10)

Fig. 1 is an elevation of a combined dial and hands for a clock or similar article, showing my new design, and

Fig. 2 is a side elevation.

I claim:

The ornamental design for a combined dial and hands for a clock or similar article, as shown.
